UNITED STATES PATENT OFFICE.

THOMAS PRENTICE, OF SOUTHBINGHAM, CONNECTICUT, ASSIGNOR TO THE PECK, STOW & WILCOX COMPANY, OF SOUTHBINGHAM, CONNECTICUT, A CORPORATION.

CHUCK FOR BIT BRACES.

Application filed November 27, 1922. Serial No. 603,524.

To all whom it may concern:

Be it known that I, THOMAS PRENTICE, a citizen of the United States, residing at Southington, in the county of Hartford and State of Connecticut, have invented a new and useful Improvement in Chucks for Bit Braces; and I do hereby declare the following, when taken in connection with the accompanying drawings and the characters of reference marked thereon, to be a full, clear, and exact description of the same, and which said drawings constitute part of this application, and represent, in—

Fig. 1 a view in side elevation of a bit-brace provided with my improved chuck.

Fig. 2 an enlarged view of the chuck in central longitudinal section, with the jaws shown partly open.

Fig. 3 a broken detail view, showing the removable safety-collar as engaged with an abutment of the shank for limiting the outward movement of the threaded operating-sleeve of the chuck.

Fig. 4 a detached plan view of the removable safety-collar.

Fig. 5 an edge view thereof.

My invention relates to an improvement in chucks for bit-braces, the object being to produce a simple, convenient and effective chuck constructed with particular reference to providing strong, convenient, attractive and effective means for limiting the outward movement of its threaded operating-sleeve, such means reducing the shock and wear of stopping the sleeve to the minimum.

In carrying out my invention, as herein shown, I employ a removable safety-collar 10 having its periphery milled, or otherwise roughened, and formed with an externally-threaded annular flange 11 adapted in diameter to be screwed into the inner end of the rotary operating-sleeve 12 of my improved chuck, the said sleeve being thereto furnished, just within its inner end, with retaining screw-threads 13 of fine pitch, in addition to its heavy, internal operating threads 14, which extend nearly throughout its length. The said collar 10 substantially corresponds in diameter to the external diameter of the operating-sleeve 12, and, therefore, does not interfere with the convenient and comfortable grasping of the same for the operation thereof, and also presents a workmanlike and attractive appearance. The said sleeve 55 is applied to a crank-type bit-brace of any

approved construction, needing no detailed description, herein generally designated by the numeral 15, and furnished with a shank 16, corresponding in diameter to the internal diameter of the safety-collar 10 and its flange 11, and provided at its outer end with outstanding external threads 17, co-acting with the threads 14 of the sleeve 12, the bottoms of the said threads 17 being co-incident with the periphery of the shank 16, so that the full diameter of the threaded outer portion of the shank exceeds the diameter of the unthreaded inner portion thereof, or the shank may be viewed as reduced in diameter at a point adjacent to its threaded portion. The said shank is formed with a diametrical slot 18 intersecting its threaded portion approximately throughout the length thereof, and receiving suitable complementary chuck-jaws 19, opened by the action of a spring 20 and closed by a cone 21 carried by a cap 22, the inner end of which is internally threaded for being screwed over an externally-threaded, integral, annular shoulder 23 formed upon the extreme outer end of the operating-sleeve 12. The said cap and sleeve, as thus combined, act as one piece, when the chuck is assembled, in controlling the jaws, and are respectively recessed to form a raceway 24 for a group of balls 25, which reduce to the minimum the friction between the cone and the cap when the cap is turned with the sleeve 12 for closing the jaws. The said safety-collar is made removable to permit the sleeve to be demounted as required for replacing the jaws, or for any other purpose which requires access to the interior of the chuck.

For the opening and closing of the jaws 19 by the action, on the one hand, of the spring 20 and, on the other hand, of the cone 21, the sleeve and shank are relatively rotated in the usual manner for their relative longitudinal movement. In opening the jaws, the sleeve moves outward with respect to the shank, and when the jaws are fully opened, the flange 11 of the safety-collar 10, mounted as described in the inner end of the sleeve, engages with the inner coil of the threads 17 upon the shank, as shown in Fig. 3, and limits the outward movement of the sleeve, whereby the user is informed by the shock of this engagement that the jaws have been brought

into their full open positions without the necessity of reversing the bit-brace and examining the chuck to ascertain the precise position of the jaws. The stopping of the 5 sleeve in the manner described also prevents it from being demounted from the shank by having its threads 14 run out of engagement with the threads 17 thereof, and thus necessitate the re-engagement of the said 10 threads for re-mounting the sleeve upon the shank. The surfaces brought into play are so large that no matter how rapidly the brace is being operated, the shock of the sudden engagement of the collar with the 15 inner coil of the threads 17 of the shank will result in no damage or jamming, and the wear is so distributed as to be negligible. The safety-collar also provides a neat and attractive finish for the inner end of the 20 sleeve and excludes all dust and chips therefrom.

I claim:

1. As a new article of manufacture, a bit-brace having a crank, a shank having integral, external threads of larger diameter than its diameter, and a jaw-receiving slot intersecting the said threads, a jaw-operating sleeve having two sets of internal threads, one set of which engages directly 25 with the external threads of the shank for the relative helical movement of the said shank and sleeve to which helical movement the said shank and sleeve are at all times limited, and the other set of threads being 30 threads of finer pitch and located just within the inner end of the sleeve, jaws located in the said slot for operation by the sleeve, and a removable stop-collar having its ex- 35

posed periphery milled and provided with an externally-threaded flange, the threads 40 of which are engaged with the said threads of fine pitch located within the inner end of the sleeve and the end of which engages with the helical outer convolution of the thread of coarse pitch upon the shank, 45 whereby the outward helical movement of the sleeve upon the shank is effectively checked without resulting wedging action.

2. As a new article of manufacture, a crank-type bit-brace having a crank, a shank formed with offstanding threads and with a jaw-receiving slot intersecting the same, a jaw-operating sleeve having internal threads intermeshing with the offstanding threads of the shank, jaws located in 55 the said slot for operation by the said sleeve, and a removable stop-collar of two diameters, of which its larger diameter corresponds to the external diameter of the sleeve, and of which the smaller diameter is 60 externally threaded for being screwed into internal threads formed in the inner end of the sleeve and adapted to co-act directly with the outer convolution of the offstanding threads upon the shank for stopping the 65 sleeve from being demounted when the crank is reversed, the larger and smaller diameters of the said stop-collar being differentiated by the thickness of the said sleeve.

In testimony whereof, I have signed this 70 specification in the presence of two subscribing witnesses.

THOMAS PRENTICE.
